UNITED STATES PATENT OFFICE.

ADELBERT E. BRONSON, OF CLEVELAND, OHIO.

DETACHABLE CAP.

1,250,957.

Specification of Letters Patent. Patented Dec. 25, 1917.

Application filed February 5, 1917. Serial No. 146,570.

To all whom it may concern:

Be it known that I, ADELBERT E. BRONSON, a citizen of the United States, residing at Cleveland, in the county of Cuyahoga and 5 State of Ohio, have invented a certain new and useful Improvement in Detachable Caps, of which the following is a full, clear, and exact description.

This invention relates to a construction 10 in which a tubular member surrounding the end of a projecting stem, is attached to the said stem in such a manner as to permit of its ready detachability.

Specifically the invention relates to an 15 improvement in dust caps for use in connection with tire valves, and the improvement provides a construction which does away with the necessity for screwing the dust cap along the valve stem for a greater or less 20 distance, but provides for the detachability of the dust cap by a simple twist or axial rotation with respect to the valve stem.

A further object of the invention is to provide a construction which will be free from 25 openings or crevices in which mud and snow may lodge, both of which features are decidedly disadvantageous in a construction of the kind herein proposed.

Generally speaking, the invention may be 30 said to comprise the elements and combinations thereof set forth in the accompanying claims.

Reference should be had to the accompanying drawings forming a part of this specification in which Figure 1 is an elevation with portions in section showing a valve stem with a dust cap embodying my invention applied thereto; Fig. 2 is an elevation with portions in section of the casing containing 35 certain portions of the invention; Fig. 3 is a top plan view of the casing shown in Fig. 2; Fig. 4 is a top plan view of an element used in the construction; Fig. 5 is a plan of the bottom of the shell or dust cap; 40 and Fig. 6 is an elevation with portions in section showing an assemblage of the elements shown in Figs. 2 to 4 inclusive.

Referring to the drawings, 1 indicates a tire valve stem of usual construction, and as 50 is well known, the stem 1 is hollow, and within the stem there is a valve and valve seat of which we will give no further description. The end of the valve stem is closed by a cap 2, and for the purpose of 55 protecting the valve cap and that portion of the valve stem which ordinarily extends

outside of the rim of the wheel, it is customary to provide a dust cap, which in most instances is threaded upon a portion of the interior thereof, and is screwed upon the 60 threaded valve stem.

In the construction herein proposed, the dust cap or shell 3 is released from its securing means by a twist or turn, imparting axial rotation to the shell 3. The lower end 65 of the dust cap is provided with a plurality of extensions which are indicated at 4, these extensions being substantially equally spaced from each other, and upon one edge thereof, each projection 4 is beveled as indicated 70 at 4^a.

Upon the valve stem 1 there is secured what I term a nut 5. This nut has a central sleeve-like portion 6, which is threaded and engages with the screw threads upon the 75 outer surface of the valve stem 1. The nut 5 has an outwardly extending flange 7 which is preferably irregular in form, and at its outer edge engages with the walls of the casing 8. This casing is of the same irregular 80 shape as the flange or extension 7, and as shown, the casing is hexagonal and the outer edge of the flange 7 is also formed hexagonal so that the casing and the nut 5 are not rotatable with respect to each other, 85 but may rotate as a unit upon the valve stem 1.

The casing 8 at one end has an inturned flange, or what I may term top portion 9. In this top portion there are formed a series of openings 10, the openings being substantially equally spaced with respect to each other, and the number of openings corresponding with the number of projections 4 upon the end of the dust cap. Intermediate 95 the openings 10, the top portion 9 of the casing 8 is formed with embossed portions 11.

The opposite end of the casing 8 has its side walls crimped in, as indicated at 12 in Fig. 1, these crimped in portions engaging 100 with the under side of the flange 7 on the nut 5 to retain it within the casing. The opening in the casing 8 which is adjacent to the flange 7 of the nut 5 is filled in with a washer 13 of leather or other suitable material. The washer fills in the threaded depressions, and also tightly engages by friction, the crimped portions of the casing 8, thus completely excluding water and dust. 105

Within the casing 8 there is a plate or washer 14. This plate or washer 14 is provided with a plurality of spaced extensions

or projections 14^a, these projections and their spacing corresponding with the number of projections upon the lower end of the dust cap. The outer portion of the plate 14 is of the same shape as the casing in which it is housed, and in this particular instance is hexagonal. Therefore, the plate 14 does not turn with respect to the casing 8, but is free to slide within the casing.

10 The plate 14 when placed within the casing, is so placed that the projections 14^a come opposite the openings 10 in the casing 8, so as normally to fill these openings completely and prevent the entrance of any 15 dust or water into the inside of the casing.

Surrounding the sleeve 6 of the nut 5 there is a spring 15. This spring at one end bears upon the extension 7 of the nut 5, and at its opposite end bears upon the inner side of the 20 plate or washer 14, thus holding the washer against the top 9 of the casing and the nut 5 against the crimped in portion 12 of the casing 8.

The projections 14^a formed upon the plate 25 14 are at one side thereof, formed with a slanting portion 4^b, the purpose of which will be presently explained.

As before explained, the cap or tubular member 3 is at its lower portion formed with 30 outwardly extending members 4 which have the beveled portions 4^a. In attaching the cap to its securing means, the extensions 4 are presented to the openings 10 in the casing 8, and these extensions 4 are pressed inwardly until they lie beneath the top or 35 cover 9 of the casing 8, then by giving the shell 3 an axial twist the extensions 4 on the cap come beneath and register with the embossed portions 11 in the cover 9 of the casing 8. When the portions 4 of the cap are 40 thus engaged by the embossed portions of the cover of the casing, the cap is held against accidental axial rotation for the projections 4 fit nicely within the embossed 45 portions 11.

When the portions 4 of the cap are presented to the openings 10 and pressed through said openings, the extensions 4 on the cap engage with the upstanding portions 50 14^a upon the plate or washer 14, and when the cap is pressed inwardly the plate or washer 14 is depressed against the action of the spring 15. As soon as the cap is given an axial twist to bring the extensions 4 of 55 the cap into registry with the embossed portions 11 of the casing 8, the plate 14 is pressed outwardly by the spring 15, and the extensions or upstanding portions 14^a of the plate 14 will enter the openings 10 in the casing 60 and will fill these openings. It will thus be seen that the openings 10 in the casing will be filled or plugged up so to speak, at all times except at the actual insertion or withdrawing of the cap from its holding 65 means.

As before explained, the extensions or upstanding portions 14^a of the washer 14 are provided with beveled ends 14^b, while the extensions 4 of the cap are provided with beveled portions 4^a.

70 These beveled portions upon the two members just discussed coöperate when it is desired to turn the cap for the purpose of removing the cap from its holding means. As the cap is given a rotation in a counter clockwise direction, the beveled portions 4^a and 14^b will engage with each other, and the continued turning of the cap will effect a cam action which will depress the plate 14 and permit the extensions 4 to come opposite the openings 10 in the casing, in which 80 position the cap is disengaged or detached.

Having thus described my invention, what I claim is:—

1. The combination of a stem, a casing 85 upon the said stem, said casing having a cover portion provided with a plurality of spaced openings, a plate within said casing, means for resiliently holding said plate against the cover of the casing, said plate 90 being provided with extensions which project through the openings in the cover, a cap having spaced extensions at the open end thereof, said extensions being adapted to be passed through the openings in the 95 casing, the extensions engaging the under side of the cover of the casing upon axial rotation of the tubular member, the extensions upon the said plate filling the openings in the cover of the casing when the 100 tubular member is thus rotated.

2. In combination a stem, a casing upon said stem, said casing having a cover which is provided with a plurality of spaced openings, the portions of the cover intermediate the openings being formed to provide recesses, a plate within said casing, means for resiliently holding the plate against the cover of the casing, a tubular member having outward extensions at the open end 105 thereof, said extensions being adapted to enter the openings in the cover of the casing and upon axial rotation of the tubular member, to move upward into the said recesses in the cover whereby the spring-pressed 110 plate may move outward into engagement with the inner side of the cover, thereby providing a substantially dust-proof structure. 115

3. In combination, a stem, a casing mounted upon said stem, said casing having a cover provided with a plurality of spaced openings, the cover intermediate the spaced openings being embossed to provide depressions, a plate within said casing, means for resiliently holding the plate against the 120 cover of the casing, said plate being provided with extensions which extend into the openings in the cover of the casing, a tubular member having a plurality of spaced extensions at the open end thereof, said ex- 125 130

tensions being adapted to pass through the openings in the casing, depressing the plate in the said casing and by an axial turning of the tubular member, the said extensions 5 on the tubular member passing into registry with the embossed depressions in the cover of the casing, the extensions upon the plate within the casing again filling the openings in the cover of the casing.

10 4. In combination, a stem, a casing mounted upon said stem, said casing having sides which extend at an angle with respect to each other, said casing also having a cover provided with spaced openings therein, a plate within the casing, said plate having sides which correspond with the sides of the casing but is prevented from turning relatively to the casing, resilient means for holding said plate against the cover of the casing, a cap having extensions at the open end thereof, said extensions being adapted to be passed through the openings in the cover of the casing and upon axial turning of the cap to engage with the inner surface of the 25 cover of the casing.

5 5. In combination, a threaded stem, a nut upon said stem, a casing surrounding the nut and in engagement with the nut, said casing having a cover provided with a plurality of spaced openings and a plurality of depressions which are interspaced with respect to the openings, a plate within said casing, said plate having engagement with the casing which prevents relative turning, 30 resilient means engaging the plate to hold it against the cover of the casing, a cap having extensions adjacent the open end thereof, said extensions being adapted to pass through the openings in the cover, and by an axial 35 turning engage the depressions in the cover of the casing.

40 6. In combination, a threaded stem, a nut upon the said stem, a casing surrounding the said nut and in engagement therewith, the 45 casing having a cover provided with spaced openings, a plate within said casing, means preventing relative rotation between the plate and said cover of the casing, a resilient member normally holding the plate 50 against the cover of the casing, said plate being provided with extensions which occupy and extend through the openings in the

cover of the casing, a cap provided with extensions adjacent its open end, said extensions being adapted to pass through the 55 openings and upon axial turning of the cap to engage with the under side of the cover of the casing.

7. In combination, a threaded stem, a nut upon the said stem, a casing surrounding the nut and engaging the nut, said casing having a cover provided with spaced openings, a plate within said casing, said plate having engagement with the casing which prevents relative turning, a resilient member 60 normally holding said plate against the cover of the casing, the plate being provided with projections which extend through the openings in the cover, each of the extensions upon the plate being beveled 65 at an end thereof, a cap provided with a plurality of spaced extensions at the open end thereof, each of said extensions being beveled at an end thereof, the extensions upon the said cap being adapted to pass 70 through the openings in the casing and upon axial turning of the cap to engage with the inner side of the cover of the casing, and upon reverse rotation the beveled portions of the extensions upon the cap and plate 75 engaging to depress the plate upon continued rotation of the cap.

8. In combination, a stem, a casing mounted upon said stem, said casing having sides which extend at an angle with respect to 85 each other, said casing also having a cover provided with spaced openings therein, a plate within the casing, said plate having sides which correspond with the sides of the casing, whereby the plate is prevented from 90 relative turning with respect to the casing, said plate being provided with extensions which normally occupy the said openings in the cover of the casing, resilient means for holding said plate against the cover of the 95 casing, a cap having extensions at the open end thereof, said extensions being adapted to be passed through the openings in the cover of the casing and upon axial turning of the cap, to engage with the inner surface of the 100 cover of the casing.

In testimony whereof, I hereunto affix my signature in the presence of two witnesses.

ADELBERT E. BRONSON.
